UNITED STATES PATENT OFFICE.

GEORGE F. DUFFEY, OF SAN FRANCISCO, CALIFORNIA, ASSIGNOR TO PACIFIC PORCELAIN WARE COMPANY, OF SAN FRANCISCO, CALIFORNIA, A CORPORATION OF CALIFORNIA.

URINAL.

1,304,752.

Specification of Letters Patent. Patented May 27, 1919.

Application filed December 18, 1916. Serial No. 137,538.

To all whom it may concern:

Be it known that I, GEORGE F. DUFFEY, a citizen of the United States, and a resident of the city and county of San Francisco, 5 State of California, have invented certain new and useful Improvements in Urinals, of which the following is a specification.

The invention relates particularly to wall urinals.

10 An object of the invention is to provide a urinal having a discharge passage which is easy of access so that it may be readily cleaned.

15 The invention possesses other advantageous features, which, with the foregoing will be set forth at length in the following description where I shall outline in full that form of the invention which I have selected for illustration in the drawings accompanying and forming part of the present specification.

In the drawings,

Figure 1 is a side view of a wall urinal, a portion thereof being shown in section.

20 Fig. 2 is a cross section taken on the line 2—2, Fig. 1.

Fig. 3 is a perspective view of the strainer.

Considerable difficulty is experienced in the maintenance of urinals, since the discharge pipe frequently becomes clogged and can only be cleaned by opening up the trap in the pipe or by disconnecting the pipe at some other place. Difficulty is also experienced in keeping them clean and sanitary, 35 since it is impossible to dislodge matter which may accumulate behind the strainer. These difficulties in prior devices I have overcome by providing a removable strainer, which when removed exposes the outlet passage.

40 The urinal of my invention comprises a bowl 2 of conventional shape, formed of

vitreous china or other comparable material, such as porcelain or enameled iron. In this specification, however, I shall refer to the 45 material as vitreous material, and it is to be understood that such term is inclusive of the various materials from which these fixtures are made. The bowl 2 is provided with an outlet passage or neck 3, which is 50 connected to a suitable drain pipe. Seated in the bowl and covering the outlet passage is a separable "bee-hive" strainer 4 of vitreous material, which in the present construction is held in place over the outlet pipe 55 by lugs 5 attached to or formed integral with the floor 6 of the bowl. The strainer is provided with apertures over more or less of its entire surface so that a blockade of the lower apertures will not prevent the 60 discharge from the bowl. The strainer is readily lifted or removed from the bowl so that the strainer and outlet pipe may be thoroughly cleaned and the fixture maintained in sanitary condition. 65

I claim:

A urinal comprising a bowl of vitreous material having a substantially horizontal bottom and a substantially vertical back and having an outlet passage at the junction of the back and bottom, a removable strainer of vitreous material having substantially vertical sides and a dome shaped top overlying said outlet passage and resting against said bottom and back and lugs disposed on 70 said bottom for removably holding said strainer in position over said outlet passage. 75

In testimony whereof I have hereunto set my hand at San Francisco, California, this 9th day of December, 1916. 80

GEORGE F. DUFFEY.

In presence of—
H. G. PROST.
